UNITED STATES PATENT OFFICE.

KARL O. NELSON, OF MILWAUKEE, WISCONSIN, ASSIGNOR TO GALLAND-HENNING MFG. CO., OF MILWAUKEE, WISCONSIN.

BALING MACHINE.

Application filed January 16, 1923. Serial No. 612,998.

To all whom it may concern:

Be it known that I, KARL O. NELSON, a citizen of the United States, and resident of Milwaukee, in the county of Milwaukee and State of Wisconsin, have invented certain new and useful Improvements in Baling Machines; and I do hereby declare that the following is a full, clear, and exact description thereof.

10 This invention relates to baling presses and is in general an improvement of my former invention disclosed in Patent Number 1,372,898, of March 29, 1921.

15 In baling presses of the type disclosed in the above noted patent, a movable press box is provided which is lowered after compression to expose the pressed bale. It is found that with baling presses of this general type considerable head room is required 20 as the press box must be sufficiently elevated to allow space below into which it may be lowered.

25 This invention is designed to overcome the above noted defect, and it has, therefore, for its primary object the provision of a baling press of the sliding press box type in which a minimum of head room is required.

30 More specifically, an object of this invention is the provision of a press of the above type with a telescopic press box.

35 Further objects are to provide a simple and compact means for manipulating the press box, to provide a more compact arrangement of press, and to generally improve and simplify the construction of baling presses.

40 An embodiment of the invention is shown in the accompanying drawing, in which:—

Figure 1 is a side elevation of the press with parts broken away to more clearly show the interior construction, the press box being in its retracted, or telescoped position.

45 Figure 2 is a side elevation showing the press box in section and in its extended position.

Figure 3 is an end elevation of the press with the parts in the position they occupy in Figure 2.

50 The press is usually mounted upon a concrete base 1 and comprises a pair of transverse I-beams 2, which may, if desired, be supported upon cross channel arms 3 to which are secured the tie-rods 4. These tie-rods extend upwardly and are secured

5 to a plurality of transverse channel irons 5, which may, if desired, be arranged in pairs in a manner similar to the channel irons 3 of the base. These upper channel irons carry a U-shaped track 6 with which the 60 roller 7 of a truck cooperate. The upper platen 8 is mounted upon the truck and carried thereby and is adapted to be slid sidewise, if desired, to permit the press to be filled from the hopper 9. During compression the platen 8 is adapted to bear against the U-shaped track 6. Other modes of feeding the press may be employed, if desired, and the movable platen 8 may be replaced by a stationary platen, if found 65 expedient. The lower or movable platen 10 is carried by a plunger 11 which cooperates with the cylinder 12 to elevate such movable platen. The platens, of course, may be provided with transverse slots or grooves to 70 receive the baling wire or straps in the usual manner.

75 The control for the plunger is secured by means of a valve 13 operated in any desired manner, as by the manually movable lever 80 14. This valve is adapted to connect the pressure supply pipe 15 with the inlet pipe 16 of the press, or to connect such inlet with the exhaust pipe 17. The details of the valve form no portion of the invention and may 85 be of the type disclosed in my above noted patent.

90 The press box comprises a stationary lower member 18 and an upper movable member 19, which is telescopically associated with the member 18 and is adapted in one position to extend upwardly to adjacent the upper platen, as shown in Figures 2 and 3, and in its other extreme or retracted position to be positioned below the elevated movable platen 11, as shown in Figure 1, to expose the compressed bale 20.

95 The movable portion 19 of the press box is provided with a rectangular bracket or guide 21 adjacent the upper portion and a practically similar guide 22 adjacent its lower portion. These brackets or guides are provided with apertured ears or lugs 23 and 24, respectively, which slide upon the tie-rods 4 and accurately guide the member 100 19 of the press box. Upper guide or bracket 21 is provided at its ends with lugs 25, with which are secured piston rods 26. These piston rods carry at their lower ends pistons 27 which cooperate with the relatively 105 110

- small, vertical cylinders 28. These cylinders are mounted upon the base, preferably upon the I-beams 2, and may, if desired, be provided with enlarged lower portions 29, 5 which may be readily secured to such I-beams. The upper and lower portions of the cylinders are provided with pipes 30 and 31, respectively, which pipes lead to simultaneously controlled valves 32.
- 10 Supply pipes 33 for the fluid under pressure are provided and communicate with the valves 32. These valves may be provided with rock arms 34 connected by a link 35, which, in turn, may be operated by 15 a manually movable lever 36. The details of the valves 32 form no part of this invention and may be of the same type as those disclosed in my above noted patent.

The operation of the press is as follows:—
20 The movable platen 11 is positioned at its lowest point, as illustrated in Figures 2 and 3, and the movable portion 19 of the press box is elevated, as shown in Figures 2 and 3. Thereafter this elongated press box is 25 filled in any suitable manner, as by shifting the upper platen and supplying it with material by means of the hopper 9, or in fact in any desired manner. After the press box has been filled, the platen 11 rises and 30 compresses the bale to the desired extent. Thereafter the valves 32 are manipulated to lower the movable portion 19 of the press box and expose the bale.

It will be seen from the detailed disclosure 35 that the usual head room required for this type of press has been materially reduced and the presses may now be mounted in buildings of a lesser height than formerly required. This is an extremely desirable 40 feature in baling presses and is secured at no sacrifice to the efficiency of the press, but is secured by an improved type of press.

It will further be seen that the tie-rods and the piston rods 26 and cylinders 28 are 45 arranged closely adjacent the press box and an extremely compact structure results.

It will further be seen that by the peculiar 50 construction of press the stresses are borne by properly positioned and designed parts and no distorting or straining action occurs, either in the operation of the compressing members proper, or in the operation of the telescopic press box.

I claim:—

- 55 1. A baling press comprising a frame having a base and an upper portion and tie rods joining said portions, an upper platen associated with said upper portion, a lower movable platen, means associated with the

lower portion of said frame for operating 60 said lower platen, a press box having a lower stationary portion cooperating with said lower platen and having an upper movable portion adapted to telescope the lower portion and cooperation with said upper platen, 65 and means carried by said base for shifting the upper movable portion of said press box.

2. A baling press comprising a frame having 70 an upper portion, a base portion, and tie rods joining said portions; an upper platen carried by said upper portion; a lower movable platen; means for moving said lower platen towards said upper platen; a telescopic press box having a lower 75 stationary portion secured to the lower portion of said frame and an upper movable portion adapted to telescope said lower portion and having guides adjacent its upper and lower portion slidably engaging said 80 tie-rods; and fluid pressure means including cylinders secured to said base and cooperating pistons operatively secured to the upper of said guides upon opposite sides 85 of said press box, for moving the upper portion of said press box.

3. A baling press comprising an upper laterally movable platen, a lower vertically movable platen, power operated means for moving said lower platen upwardly, a press 90 box having a stationary member adjacent its lower portion, and a movable telescopically related member normally adjacent its upper portion, and power operated means for controlling the position of said upper member, 95 said last mentioned power operated means being independent of said first mentioned power operated means.

4. A baling press comprising a frame including an upper portion, a base, and tie 100 rods joining said upper portion and base; an upper laterally movable platen; a lower vertically movable platen; means operated by fluid pressure for moving said lower platen towards said upper platen; a press box having telescopic portions, one of said portions being movable and adapted to slide downwardly to expose a pressed bale; and means secured to said base and operated by fluid pressure for sliding the movable portion of said press box upwardly and downwardly.

In testimony that I claim the foregoing I have hereunto set my hand at Milwaukee, in the county of Milwaukee and State of 115 Wisconsin.

KARL O. NELSON.
